DOOR MOUNTING MECHANISM

Maurice Glenn Bundy, Kansas City, Kans., assignor to H. H. Potter, Kansas City, Mo.

Application February 5, 1937, Serial No. 124,217

11 Claims.

(Cl. 20—16)

This invention relates to doors and door mechanisms, and particularly to those for use in wardrobes, closets or like places where a door or group of doors are mounted and adapted to recede when opened.

The principal object of the invention is to provide a mounting for doors of this character which is of simple and relatively inexpensive construction, and which is adapted for easy installation and adjustment.

It is also an important object to provide an operating mechanism whereby the doors may be opened or closed simultaneously and may be readjusted and kept in perfect operating condition after the usual shrinkage and settlement occurs in the structure in which the doors are installed.

A further object of the invention is to provide a construction wherein the door or doors are guided for recession within the wardrobe by means of tracks carried by the respective doors.

Other important objects are to provide a track on the respective doors whereby the companion doors are maintained in the same relative position while travelling in either opening or closing directions; and to provide a guiding mechanism which changes the guiding leverage on the doors to permit them to be opened and closed by forces applied in a constant direction to the door being moved.

In accomplishing these and other objects of the invention, as hereinafter pointed out, I have provided improved details of structure, the preferred form of which is illustrated in the accompanying drawings, wherein:

Fig. 1 is a perspective view of a wardrobe equipped with doors embodying the features of the present invention.

Fig. 2 is a cross-section through the upper portion of the wardrobe on the line 2—2 of Fig. 1, illustrating the doors in open position.

Fig. 3 is a similar section showing the doors in closed position, and taken on the line 3—3 of Fig. 5.

Fig. 4 is a horizontal section through the upper portion of the wardrobe on the line 4—4 of Fig. 2.

Fig. 5 is a similar horizontal section on the line 5—5 of Fig. 3.

Fig. 6 is an enlarged detail perspective view of the upper inner side portion of the left-hand door, particularly illustrating the operating mechanism therefor.

Fig. 7 is a section illustrating support of the lower end of one of the doors.

Referring more in detail to the drawings:

1 designates a wardrobe, for example one that

is built into the wall 2 of a schoolroom, and which includes a back 3 and sides 4 and 5 joining the back with the jamb portions 6 and 7 of a front opening 8 to provide a recess 9 coextensive with the width and height of the opening.

In the wardrobe illustrated the opening is normally closed by a double pair of doors 10 and 11, however, a greater number of pairs of doors may be used depending upon the width of the opening. The doors 12—13 and 14—15 of the respective 10 pairs are of shorter height than that of the opening to provide a ventilating space 16 between the bottom ends of the doors and the floor 17 of the room. The combined width of the doors is sufficient to completely close the width of the opening and provide overlapping rabbets 18 and 19 at the respective side edges of each door to engage with the adjoining edge of adjacent doors and to engage the stops 20 and 21 at the sides of the door opening.

Fixed to the inner face of each door adjacent the upper and lower ends thereof, are bearing brackets 22 and 23 having aligning vertical bores 24 to mount a vertical shaft or spindle 25 on which the doors are adapted to pivot as later described. The spindle is of sufficient height to project beyond the lower and upper ends of the door to engage in bearings 26 and 27 of upper and lower mounting arms 28 and 29 respectively. One of the lower mounting arms 29 is clearly shown in Fig. 7 and has a downwardly opening socket 30 formed on the end thereof opposite the bearing 27 to mount a trunnion member 31. The trunnion member 31 includes a threaded shank 32 threadedly mounted in the socket 30 and a depending head 33 having a polygonal portion 34 to be engaged by a suitable wrench whereby the spindle is adjusted in the socket as later described.

The shank of the spindle is normally retained in adjusted position by a set screw 36 that is threaded through the wall of the socket and has its end 37 bearing against the threads of the shank. Depending from the head 33 is a reduced extension 38 forming an annular bearing race 39 and trunnion for ball bearings 40 that are supported in a cooperating race 41 in a floor flange 42, the flange 42 being secured to the floor in the vertical plane of the opening by fastening devices, such as screws 43.

The lower bearing bracket 23 preferably carries an antifriction thrust bearing 44 whereby the door is adjustably sustained on the arm 29 by means of a set screw 45 that is threaded through a portion of the arm and engages against a washer-like bearing race 46 inset into the lower

end of the bracket and cooperating with a shoul-
dered bearing race 47 having an annular shoulder
48 engaging an annular stop flange 49 provided
in the upper end of the bearing bracket. Mount-
ed between the races are ball bearings 50 to facili-
tate swinging movement of the door on its
shaft 25.

Extending across the top of the door opening
is an angle bar 51 having an inwardly directed
flange 52 to support a similar mounting arm 28
for the upper end of the door. The arm 28 has
a bearing 26 supporting the upper projecting end
of the shaft and a bearing 55 on its opposite end
that is rotatably mounted on a stud 56 having
a base flange 57 attached to the angle flange 52
in vertical alignment with the floor flange, pre-
viously described, the flange 57 being secured
to the angle by fastening devices 58.

Each of the doors is equipped with a mounting
as above described, and is adapted to swing about
its respective shaft and to be carried by its arms
into the door opening for parallel alignment with
the end walls of the wardrobe as shown in Fig. 1,
the arms for the respective doors being arranged
so that the doors of each pair swing away from
each other and the adjacent doors in adjacent
pairs swing toward each other. In order to con-
trol pivotal movement of the door it is necessary
to provide each door with guiding means as now to
be described.

Secured to the upper edge of each door is a
guide member 59 having a horizontal flange 60
overlapping the upper edge of the door and de-
pending ears 61 engaging against the inner face
35 of the door wherethrough fastening devices 62
are extended as shown in Fig. 6. Projecting in-
wardly from the bracket in the plane of the
flange 60, is a substantially arcuate shaped arm
63 having a slot 64 forming a guide track for a
40 roller 65. The roller 65 is carried on a spindle
66 depending from an arm 67 that is attached
to the flange 52 of the angle bar and projects
inwardly of the wardrobe above the arcuate track.
The roller 65 preferably has a flange 68 engag-
45 ing the under side of the arcuate arm to retain
the roller within the slot 64. The arcuate arm
is offset laterally from the axis of the shaft 25
to clear the bearing end 26 of the arm 28 as
shown in Fig. 6. The arm is, therefore, notched
50 as at 69 to accommodate the projecting end of
the shaft. Each door is equipped with a guide
as above described, so that when the meeting
edges of the doors in each pair are swung out-
wardly the pivoting movement of each door on
55 its shaft 25 is controlled by the arcuate track
with the rollers 65 acting as fulcrums. The arcu-
ate tracks therefore rock about the rollers 65 to
cause swinging movement of the mounting arms
inwardly of the recess thereby carrying the doors
60 from the positions shown in Fig. 5 to those shown
in Fig. 4.

The shape of the track slots and the direct
mounting of the track members on the doors re-
sults in a variable guiding leverage so that the
65 forces acting to move the doors may be applied
in a constant direction relatively to the doors.
In order that all of the doors may swing together
in unison, the upper arms 28 are provided with
levers 70 mounted on the projecting ends of the
70 studs 56 and have angular portions 71 provided
with slots 72 to pass studs 73 that are carried
on reinforcing webs 74 of the arms 28, the studs
being provided with nuts 75 whereby the triangu-
lar portions of the arms are clamped to the arms
75 28. The levers 70 include projecting portions 76

that are connected with the levers of correspond-
ing doors in each pair by means of connecting
links 77 and 78 respectively, the levers being con-
nected with the links by pivot pins 79 as shown
in Fig. 6.

In order to interconnect the pairs of doors, the
angle 51 carries a bracket 80 that is located over
the pair of doors and pivotally mounts a bell
crank lever 81 having one arm 82 thereof con-
nected by a link 83 with the connecting link 78
10 while the other arm 84 of the bell crank is piv-
otally connected by a link 85 with the arm 28
for the door 14. In the illustrated instance, the
door 12 is the master door and is provided with
an operating handle 86 wherewith the door may
be grasped to swing it to open position. Simul-
taneously with movement of the door 12, the door
14 is also moved by means of the connecting
link 77. Simultaneously with movement of the
door 14, the connecting link 85 actuates the bell
crank 81 to effect reciprocation of the connecting
link 78 through the link 83 so that the doors 13
and 15 are moved to the open position, as shown
in Fig. 4.

After the doors have been installed as above
described, they are adjusted so that when the
rabbet grooves in the side edges thereof are inter-
engaged they are all positioned in a common
plane. This is accomplished by adjusting the
relative position of the levers 70 with the arms 28.
35 This adjustment is accomplished by loosening the
nuts 75, moving the arms 70 relative to the arms
28, and then retightening the nuts to hold them
in adjusted position. The doors are aligned for
height by manipulation of the set screws 45 and
adjustment of the spindles in the sockets 30 of
the arms. After these adjustments the doors are
supported in their desired relative relation and
they can be kept in this relation by making simi-
lar adjustments whenever necessary, as in case
of shrinkage and settling of the structure in
which they are installed.

From the foregoing it is obvious that I have
provided a door arrangement for a wardrobe,
closets and the like, which is of simple and in-
expensive construction, is readily installed, and
which may be kept in operative condition with
minimum adjustments.

Although I have described and illustrated a
plurality of doors and their operating mechanism
as installed within a wardrobe, it is obvious that
one or more doors would swing and operate in
the same manner.

What I claim and desire to secure by Letters
Patent is:

1. In an apparatus of the character described,
pairs of doors, means pivotally and swingingly
mounting the doors in a door opening, a guide
track on each of the respective doors, means en-
gaging the guide tracks to control movement of
the doors to and from open position, and means
operably connecting the pairs of doors whereby
the doors are operated in unison.

2. In an apparatus of the character described,
pairs of doors, means swingingly supporting the
65 doors for bodily movement on an arc into a door
opening, means pivotally mounting the doors on
said door swinging means for movement about
an axis of rotation during swinging movement of
the doors on said arcs, means operably connect-
70 ing the swinging means for the respective doors,
and means for effecting pivotal movement of all
the doors incidental to operation of the door
swinging means of one of the doors.

3. In an apparatus of the character described,

5 a door, a spindle member on the door, arms pivotally connected with the spindle member for swingingly mounting the door in a door opening, a guide track carried by the door, and means engaging with the guide track for controlling movement of the door to and from open position.

10 4. In an apparatus of the character described, pairs of doors, a spindle member carried by each individual door, arms connected with the spindle members, means pivotally anchoring the arms in a door opening for movement of the spindle members on an arc about the axes of said anchoring means to swingingly mount the individual doors, operating levers connected with said arms, means 15 connecting the operating levers of selective doors in each pair, means connecting the levers on the other of said doors, means interconnecting said connecting means for reversing movement of one door in each pair relatively to the other and whereby all of the doors are operated in unison incidental to operation of one of the doors, and means for controlling movement of each of the individual doors.

20 5. In an apparatus of the character described, pairs of doors, a spindle member for each individual door, means pivotally mounting each door on its spindle member, arms connected with the respective spindle members, means pivotally anchoring the arms in a door opening, for movement of the spindle members on an arc about the axes of said anchoring means to swingingly mount the individual doors, levers connected with said arms, means connecting the levers with selective doors in each pair, means connecting the levers on the other of said doors, reversing means interconnecting said connecting means whereby all of the doors are operated in unison incidental to operation of one of the doors, and means for controlling movement of each of the individual doors including means for effecting reverse pivotal movement of the doors in each pair.

25 6. In an apparatus of the character described, a door, a spindle member on the door, arms pivotally connected with the spindle member, means pivotally anchoring the arms in a door opening for movement of the spindle member on an arc about the axis of said anchoring means to swingingly mount the door in a door opening, an arcuate guide member carried by the door and having an arcuate slot forming a guide track, a roller engaging in the guide slot for controlling movement of the door, and means supporting the roller.

30 7. In an apparatus of the character described, a door, a spindle member on the door, arms pivotally connected with the spindle member, means

35 pivotally anchoring the arms in a door opening for movement of the spindle member in an arc about the axis of said anchoring means to swingingly mount the door in a door opening, an arcuate guide track carried by the door, means engaging with the guide track for controlling movement of the door, and means for adjustably raising the door relatively to said arms to adjust the door in said opening.

40 8. In an apparatus of the character described, pairs of doors, a spindle member carried by each individual door, arms adjustably connected with the spindle members, means pivotally anchoring the arms in a door opening, levers connected with said arms, means connecting the levers with selective doors in each pair, means connecting the levers on the other of said doors, and means interconnecting said connecting means whereby all of the doors are operated in unison incidental to operation of one of the doors.

45 9. In an apparatus of the character described, pairs of doors, an angle member extending across the top of all the doors, floor flanges below the respective doors, lever arms respectively carried by the angle member and said floor flanges for swingingly mounting the doors in a door opening, means pivotally mounting the doors on said swinging means, guide tracks on each of the respective doors, means engaging the guide tracks to control movement of the doors to and from open position, and means operably connecting the pairs of doors whereby the doors are operated in unison.

50 10. In an apparatus of the character described, a door, means swingingly supporting the door for bodily movement on an arc into a door opening, means pivotally mounting the door on said swinging means for movement about an axis of rotation during swinging movement of the door on said arc, a guide track fixed to the door, and means engaging with the guide track for controlling movement of the door when moved to and from open position relatively to the door opening.

55 11. In a door mounting, a door, means pivotally mounting the door to swing about an axis intermediate its side edges, means pivotally supporting said mounting means to swingingly position the door for bodily movement into and out of a door opening, a substantially arcuate guide track on the door, and means fixed relatively to the door and engaging said guide track for guiding the door in swinging movement on said axis when bodily moved into and out of said door opening.

MAURICE GLENN BUNDY. 55
